(57) **CLAIM**

The ornamental design for a softball or baseball glove, as shown.

DESCRIPTION

FIG. 1 is a perspective view of a softball baseball glove showing my new design;

FIG. 2 is a left side elevational view thereof;

FIG. 3 is a right side elevational view thereof;

FIG. 4 is a front elevational view thereof;

FIG. 5 is rear elevational view thereof;

FIG. 6 is a bottom plan view thereof; and,

FIG. 7 is a top plan view thereof.

The broken line showing of the glove web is for illustrative purposes only and forms no part of the claimed design.
